UNITED STATES PATENT OFFICE.

JAMES D. MITCHELL, OF LAKewood, OHIO.

TRUING DEVICE FOR VALVE-SEATS.

No. 821,367.

Specification of Letters Patent.

Patented May 22, 1906.

Application filed March 26, 1904, Serial No. 200,219.

To all whom it may concern:

Be it known that I, JAMES D. MITCHELL, a citizen of the United States, residing at Lakewood, in the county of Cuyahoga and State of Ohio, have invented certain new and useful Improvements in Truing Devices for Valve-Seats, of which the following is a specification.

This invention relates to that class of tools or riggings which are used to retrue worn valve-seats.

The principal object of the invention is to provide a valve-seat-retruing rigging which can be attached to any ordinary pump or like device having a valve-seat requiring retruing and adjusted so as to be alined perfectly with the seat.

One of the features of the invention has reference to a novel means of adjusting the truing device from a true perpendicular to a slight inclination in any direction to perfectly aline the truing-blade with the seat to be trued.

Another feature has reference to the spring device for pressing the truing-tool against the seat to be trued.

The invention also has reference to certain other novel features or details of construction, among which are a recessed holding-block for the tool which is arranged so that the entire cutting-surface of the blade is exposed and a long tubular centering-support for the shaft of the facing-tool, all of which will be fully and clearly hereinafter described and claimed, reference being had to the accompanying drawings, in which a preferred adaptation of the invention is shown.

Figure 1 is a longitudinal section through the pumping-cylinder of a steam-pump, showing the improved valve-seat-truing device in operative position thereon. Fig. 2 is an enlarged central vertical section through the support for the truing device, showing the truing device set at a slight angle. Fig. 3 is a view similar to Fig. 2, showing the truing device in a vertical position. Fig. 4 is an enlarged detached central vertical section through the split sleeve. Fig. 5 is an enlarged detached side elevation of the split sleeve. Fig. 6 is an enlarged detached bottom plan view of the split sleeve. Fig. 7 is an enlarged detached view of the link washer. Fig. 8 is an enlarged central vertical section through the truing device and its support. Fig. 9 is an enlarged detached end view of the recessed holding-block. Fig. 10 is an enlarged detached side elevation of the recessed holding-

block. Fig. 11 is an enlarged detached bottom view of the recessed holding-block. Fig. 12 is an enlarged detached top plan view of the vertical operating rod or stem. Fig. 13 is an enlarged detached face view of one of the cutting or grinding blades. Fig. 14 is a section on line *a a*, Fig. 13. Fig. 15 is a detached plan view of the support for the truing device. Fig. 16 is an enlarged detached top plan view of the interiorly-screw-threaded clamp.

In referring to the drawings for the details of construction, like numerals designate like parts.

The vertically-extending shaft or stem 1 has its lower end 2 reduced and screw-threaded, as shown in Fig. 8, and a recessed holding-block formed as shown in Figs. 8, 9, 10, and 11 is provided with a screw-threaded opening in its top surface, into which the screw-threaded end 2 of the shaft fits. The recessed holding-block has an upper tubular portion or hub 3, in which the screw-threaded opening is formed, and a rectangular-shaped lower holding or gripping portion 4, which is provided with a longitudinally-extending recess or depression 5. This recessed holding-block has a longitudinal cut or split 6, extending centrally through the gripping portion 4 and through the lower portion of the hub 3, and the separated parts of the gripping portion 4 are drawn together by means of two transversely-extending screw-bolts 7.

The cutting or grinding blade 8 is formed substantially as shown in Figs. 13 and 14 and is secured in place in the recessed block by fitting it into the recess or depression 5 and tightening the screw-bolts 7, thus gripping the blade 8 securely between the two parts of the gripping portion of the recessed block. The grinding-blade 8 has its cutting edges arranged so as to face toward the center of the blade—that is, the cutting edges of one half of the blade are formed oppositely to the cutting edges of the other half of the blade, as shown in Figs. 13 and 14, and the angle of the cutting edges across the face of the blade may be varied to suit different kinds of work. By forming the cutting edges of each half of the blade in opposite directions both halves of the blade are grinding while the blade is being rotated, while if the cutting edges were formed in the same direction only one-half of the blade would be grinding.

The vertical shaft or stem 1 is supported in a vertically-extending tubular centering-

sleeve 9, so as to rotate therein, and the tubular centering-sleeve 9 is adjustably supported in a split collar 10, which is formed integrally with an angular supporting-bar 11. (See Fig. 8.) The split collar 10 is provided with an opening 12 of larger diameter than the diameter of the sleeve 9, and said opening 12 is formed at a slight angle to the perpendicular, as shown in Fig. 15. A short split ring or sleeve 13, which has an outside diameter equal to the diameter of the opening 12, encircles the centering-sleeve 9 and is fitted into the opening 12. The opening 14 in this ring or sleeve 13 is also formed at a slight angle to the perpendicular, and the vertical split or cut 15 is formed therein in a position such that when it is alined with the split or cut 16 in the split collar 10 the tubular sleeve 9 and the shaft or stem 1 will extend in a true vertical direction. The split ring or sleeve 13 is provided with an annular flange 17 at its upper end, which rests upon the top surface of the collar 10, and the sleeve 13 is locked to the tubular centering-sleeve 9 by a set-screw 18. (See Fig. 8.) The ring or sleeve 13 is also clamped tightly in the split collar 10 by means of a screw-bolt 19, which screws through laterally-projecting ears on said collar 10. (See Figs. 8 and 15.)

The lower end of the tubular sleeve 9 is exteriorly screw-threaded, and a split tubular part 20, having a reduced lower opening through which the shaft 1 passes, is screwed upon the lower end of the sleeve 9, to which it is clamped by means of a screw-bolt 21. The bolt 21 is screwed through openings in laterally-extending ears 22.

A washer 23 is placed upon the top surface of the tubular portion 3 of the recessed holding-block, and a spiral spring 24 encircles the lower end of the shaft or stem 1 and is held in place by the interiorly-screw-threaded part 20 and the washer 23. (See Fig. 8.)

The horizontal portion of the angular supporting-bar 11 is provided with an elongated opening or slot 25, through which a bolt may be passed to secure the support to the pump-body. (See Fig. 1.)

A split collar 26 is clamped around the upper end of the shaft or stem 1 above the tubular centering-sleeve 9, so as to secure the shaft 1 in place in the sleeve 9.

The upper end 27 of the shaft 1 is of square or other irregular form in cross-section, and a bar or crank 28, which is provided with an opening or openings of similar form as the upper end 27 of the shaft 1, is fitted upon the end of the shaft 1 and forms a means for rotating said shaft. The bar or crank 28 may have a short handle 29 attached thereto, by which it may be rotated.

The shaft 1 has a slight up-and-down movement, which is provided for by the spiral spring 24, and by this means the blade 8 is pressed upon the valve-seat with a spring tension.

It will be seen by referring to Figs. 2 and 3 that by loosening the screw-bolts 18 and 19 and turning the sleeve 13 the shaft 1 may be tilted at a slight angle to the perpendicular or may be adjusted to a true vertical position, as shown in Fig. 8. The purpose of this is to provide for any slight irregularity in the surface to which the angular supporting-bar 11 is secured, which, if the shaft 1 were secured in the collar 10 without means of adjustment, would cause the blade 8 to grind the valve-seat at an angle instead of at a true horizontal plane.

A link washer 30 may, if necessary, be interposed between the angular supporting-bar 11 and the surface to which it is secured, as shown in Fig. 1, so as to raise the supporting-bar 11 a sufficient distance from the valve-seat.

The operation is as follows: In truing the seat of a pump-valve similar to that shown in Fig. 1 the bonnet of the pump is removed and the device is attached thereto by securing a bolt through the slot 25 in the angular supporting-bar. The cutting-blade 8 is alined with the seat to be trued by the eccentric adjustment of the split collar 10 and sleeve 13 and is brought in contact with the face of the seat and then locked against anything but downward and rotating movement by tightening the screw-bolts 18 and 19. The shaft 1 is now rotated by means of the bar or crank 28 until the valve-seat is ground to a true surface.

I claim as my invention—

1. In a valve-seat-truing device, a stem carrying a cutting-blade at its lower extremity, a centering-sleeve having an opening extending therethrough at an angle to the periphery of said sleeve in which the stem is rotatably mounted and a supporting-bar bolted to a suitable portion of the device having the seat to be trued and having a split collar provided with an opening extending therethrough at an angle to the periphery of said collar in which the centering-sleeve is adjustably supported, substantially as set forth.

2. A valve-seat-truing device having a vertical stem, a recessed holding-block on the lower extremity of said stem, a cutting-blade supported by said holding-block, a centering-sleeve having an opening extending therethrough at an angle to the periphery of said sleeve in which the vertical stem is rotatably mounted, a supporting-bar bolted to a suitable portion of the device having the seat to be trued and having a split collar formed integral with said bar and provided with an opening extending therethrough at an angle to the periphery of said collar in which the centering-sleeve is adjustably supported, substantially as set forth.

3. In a valve-seat-truing device, a stem provided with a cutting-blade, a centering-sleeve in which the stem is rotatably mounted, a supporting-bar bolted to a suitable por-

tion of the device having a seat to be trued and having a split collar provided with an opening formed at a slight angle to the perpendicular and of larger diameter than the diameter of the sleeve and a split ring fitting in the split collar and having an outside diameter equal to the diameter of the opening in the split collar and an opening formed at a slight angle from the perpendicular in which the centering-sleeve is adjustably supported, substantially as set forth.

4. A valve-seat-truing device having a vertical stem, a recessed holding-block on the lower extremity of said stem, a cutting-blade supported by said holding-block, a centering-sleeve having an opening formed at a slight angle to the perpendicular in which the vertical stem is rotatably mounted, a supporting-bar bolted to a suitable portion of the device having the seat to be trued and having a split collar provided with an opening formed at a slight angle to the perpendicular in which the

centering-sleeve is adjustably supported, substantially as set forth.

5. A valve-seat-truing device having a vertical stem, a recessed holding-block on the lower extremity of said stem, a cutting-blade supported by said holding-block, a centering-sleeve in which the vertical stem is rotatably mounted, a supporting-bar bolted to a suitable portion of the device having a seat to be trued and having a split collar provided with an opening formed at a slight angle to the perpendicular and of larger diameter than the diameter of the sleeve, a split ring having an outside diameter equal to the diameter of the opening in the split collar and an opening formed at a slight angle from the perpendicular in which the centering-sleeve is adjustably supported, substantially as set forth.
